UNITED STATES PATENT OFFICE.

WILLIAM E. COYAN, OF HOMESTEAD, PENNSYLVANIA, ASSIGNOR OF TWO-FIFTHS TO JOHN K. SKELLEY, OF MCKEESPORT, PENNSYLVANIA.

HARDENED RAILROAD-RAIL.

SPECIFICATION forming part of Letters Patent No. 694,838, dated March 4, 1902.

Application filed November 20, 1901. Serial No. 83,037. (No model.)

To all whom it may concern:

Be it known that I, WILLIAM E. COYAN, a citizen of the United States, residing at Homestead, in the county of Allegheny and State of Pennsylvania, have invented new and useful Improvements in Hardened Railroad-Rails, of which the following is a specification.

My invention relates to a new article of manufacture, a railroad-rail with hardened ends, and a process for producing the same.

It is well known that in the case of tracks laid over marshy ground or on an uneven road-bed that the fish-plates become loosened, the rails work up and down, and the ends get out of line with each other. This movement of the rails results in the battering up of the ends and the rounding off of the corners thereof, thereby destroying the rail, which has to be discarded long before the body is worn out.

It is with the purpose of preventing the ready battering of the ends of the rail, and thereby prolonging the lives of the same, that my invention was made.

In the accompanying drawings I have, in order to make my invention fully understood, selected for illustration a simple form of apparatus by which my objects can readily be carried into effect, in which—

Figure 1 is an end view of a table with rails thereon and the sprays in position, together with their supply-pipes. Fig. 2 is a plan view of the same. Fig. 3 is a perspective view of a street-railway rail.

Like numerals of reference designate like parts in the different views of the drawings.

The numeral 1 designates a horizontal table long enough to accommodate rails 2 of standard length. An abutment 2^a is secured to one end of the table and serves to limit the movement of the rails and to bring their ends in the same straight line. Located at each end of the table 1 and near one side thereof is a spray 3, having a plurality of perforations 3^a therein. The spray 3 is designed to spray the ends of several rails at once. A supply-pipe 4 of the spray 3 is connected to a tank 5 for containing a mixture for case-

hardening. A valve 6 regulates the flow of liquid to the spray. A trough 7 is set on the floor and located beneath the spray 3 in order to catch and save the fluid from the tank 5. A steam-pipe 8, directed toward the trough, serves to quench the fire in case combustible ingredients are used in the case-hardening mixture. A pump 9, provided with connections 10 and 11, returns the fluid to the tank 5. While any case-hardening mixture will answer, I prefer to use a solution comprising pitch and yellow prussiate of potash. This mixture must be heated at first, after which it will be kept hot by the heat of the rails.

Located just opposite the sprays 3, but on the opposite side of the table therefrom, are two sprays 12, of about twice the length of the spray 3. Pipes 13, connected to some source of water-supply, serve to feed the spray 12.

In operation the rails are passed through the finishing-rolls and are then sawed off and placed on the table 1. They are first placed beneath the sprays 3 and the case-hardening fluid turned on both ends thereof, after which they are left lying until the mixture has thoroughly burned on. The heat remaining in the rail is sufficient for the purpose. As soon as the case-hardening has been completed the rails are transferred to the other side of the table and the water turned on their ends by means of the sprays 12. The water is left running until there is not enough heat remaining in the bodies of the rails to draw the temper, after which the rails are removed to make room for a new batch.

I do not wish to confine myself to the structure of apparatus herein disclosed to carry my invention into effect.

Having thus described my invention, what I claim as new, and wish to secure by Letters Patent, is—

1. A new article of manufacture, a steel rail having its ends only hardened.
2. A steel rail having its ends only hardened by treating them when hot with case-hardening fluid and then treating them with a tempering fluid, substantially as described.

3. A new article of manufacture, a steel rail having its ends only hardened to a greater degree than the main portion of the body thereof.
4. A new article of manufacture, a steel rail
- 5 having its ends only hardened at the head to a greater degree than the remaining portion and body thereof.

In testimony whereof I have hereunto set my hand in presence of two subscribing witnesses.

WILLIAM E. COYAN.
